UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

GRAVITY-ROLLER SIDE BEARING.

No. 803,241.

Specification of Letters Patent.

Patented Oct. 31, 1905.

Application filed July 6, 1905. Serial No. 268,576.

To all whom it may concern:

Be it known that I, JOHN F. O'CONNOR, a citizen of the United States, residing in Chicago, in the county of Cook and State of Illinois, have invented a new and useful Improvement in Gravity-Roller Side Bearings, of which the following is a specification.

My invention relates to improvements in gravity-roller side bearings for railway-cars. The object of my invention is to provide a gravity-roller side bearing of a strong, efficient, and durable construction in which the rollers interposed between the upper and lower bearing-plates will be automatically kept in central or proper relative position in respect to the upper and lower bearing-plates when the car after passing around a curve again passes onto a straight track, in which the rollers may be kept properly spaced, and in which the rollers will automatically return by their own gravity and that of the load thereon to their normal or central position.

My invention consists in the means I employ to practically accomplish this object or result—that is to say, it consists, in connection with the upper and lower bearing-plates, one secured to the body-bolster and the other to the truck, the lower bearing-plate being furnished with reversely-inclined or gravity tracks for the rollers, the tracks for the rollers in the upper and lower bearing-plates being preferably curved about the king-bolt as a center, of bearing-rollers preferably conical in form to correspond to the curvature of the upper and lower tracks between which they are interposed, a pair of spacers having pivot-studs fitting in the rollers and an intermediate pivot-stud to receive a roller regulating or positioning device, and a roller regulating or positioning device pivotally connected to said spacer-plates and engaging at its upper end the upper bearing-plate and at its lower end the lower bearing-plate.

My invention also consists in the novel construction of parts and devices and in the novel combinations of parts and devices herein shown or described.

In the accompanying drawings, forming a part of this specification, Figure 1 is an elevation, partly in vertical section, of a roller side bearing embodying my invention. Fig. 2 is a plan view, partly in horizontal section. Fig. 3 is a vertical section on line 3 3 of Fig. 2. Fig. 4 is a detail perspective view of the

roller regulating or positioning device, and Fig. 5 is a detail perspective view of one of the roller-spacer devices.

In the drawings, A represents the base or lower bearing-plate, the same being secured to the truck-bolster, and B is the upper bearing-plate, the same being secured to the body-bolster of the car. The lower bearing-plate A is provided with roller-tracks a for the rollers C C. Each of the roller-tracks a is furnished with reverse inclines a' a'', so that the rollers C C will tend to return to their central or normal position by their own gravity and by that of the load resting upon them. The roller-track A is preferably curved about the king-bolt as a center, as will be readily understood from Fig. 2 of the drawings. The upper bearing-plate B has a roller-track b, similarly curved about the king-bolt as a center. The bearing-rollers C C are preferably of conical form to correspond to the curvature of the track about the king-bolt. The bearing-rollers C are each furnished with central holes or bearings e to receive the pivot-studs d of the spacer plates D D, two of the same being preferably employed, one upon the inside and the other upon the outside. The spacers D D are also furnished with middle pivot-studs d', which fit in the pivot-hole f of the roller equalizing or positioning device F, which is thus pivotally mounted on the roller-spacers D. The roller-positioning device F is furnished with a pivot or bearing f'', which fits in a suitable slot or recess a' in the base or lower bearing-plate A, and with a similar pivot or bearing f'', which fits in a corresponding slot or recess b' in the upper bearing or cap plate B. The roller-positioning device F thus connects the upper and lower bearing-plates, the spacers, and rollers and insures the rollers being kept in normal position and proper relations to the other parts. The base or lower bearing-plate A is provided with a removable guide-plate A', secured thereto by bolts or rivets a'', and which overhangs the guide-flanges b' on the upper or cap plate B. The upper or cap plate B is provided with depending sides b'', which embrace the spacers D D on each side, and thus hold the parts in their assembled position.

I claim—

1. In a roller side bearing for railway-cars, the combination with upper and lower bear-

ing - plates, the lower bearing - plate being furnished with reversely - inclined roller-tracks, of bearing-rollers interposed between the upper and lower bearing-plates, roller-spacers having pivot-studs fitting in the rollers and furnished with intermediate pivot-studs, and a roller regulating or positioning device pivotally connected to the spacers, and having a pivotal connection at its upper end with the upper bearing-plate and a pivotal connection at its lower end with the lower bearing-plate, substantially as specified.

2. In a roller side bearing for railway-cars, the combination with upper and lower bearing - plates, the lower bearing - plate being furnished with reversely - inclined roller-tracks, of bearing-rollers interposed between the upper and lower bearing-plates, roller-spacers having pivot - studs fitting in the rollers and furnished with intermediate pivot-studs, and a roller regulating or positioning device pivotally connected to the spacers, and having a pivotal connection at its upper end with the upper bearing-plate and a pivotal connection at its lower end with the lower bearing-plate, said upper bearing-plate having depending sides embracing the roller-spacers, substantially as specified.

3. In a roller side bearing for railway-cars, the combination with upper and lower bearing - plates, the lower bearing - plate being furnished with reversely - inclined roller-tracks, of bearing - rollers interposed between the upper and lower bearing - plates, roller-spacers having pivot-studs fitting in the rollers and furnished with intermediate pivot-studs, and a roller regulating or positioning device pivotally connected to the spacers, and having a pivotal connection at its upper end with the upper bearing-plate and a pivotal connection at its lower end with the lower bearing - plate, said upper bearing - plate having depending sides embracing the roller-spacers, and provided with guide-flanges, and said lower bearing-plate having guide-plates secured thereto and overhanging the guide-flanges on the depending sides of the upper bearing-plate, substantially as specified.

4. In a roller side bearing for railway-cars, the combination with upper and lower bearing-plates, of a bearing-roller interposed between the same, a roller regulating or positioning device connecting the upper and lower bearing-plates and means connecting said positioning device with the bearing-roller, said lower bearing-plate being provided with a reversely-inclined track for the roller, to cause the roller to return to position by gravity, substantially as specified.

5. In a roller side bearing for railway-cars, the combination with upper and lower bearing-plates, of a plurality of rollers interposed between said bearing-plates, a spacer having

65 pivot-studs fitting in the rollers and an intermediate pivot-stud, and a roller regulating or positioning device pivotally connected to said spacer and engaging at its upper end the upper bearing-plate and at its lower end the lower bearing-plate, substantially as specified.

6. In a roller side bearing for railway-cars, the combination with upper and lower bearing-plates, of a plurality of rollers interposed between said bearing-plates, a spacer having 75 pivot-studs fitting in the rollers and an intermediate pivot-stud, and a roller regulating or positioning device pivotally connected to said spacer and engaging at its upper end, the upper bearing-plate and at its lower end, 80 the lower bearing-plate, said upper bearing-plate having depending sides embracing the spacer, substantially as specified.

7. In a roller side bearing for railway-cars, 85 the combination with upper and lower bearing-plates, of a plurality of rollers interposed between said bearing-plates, a spacer having pivot-studs fitting in the rollers and an intermediate pivot-stud, and a roller regulating or positioning device pivotally connected to 90 said spacer and engaging at its upper end, the upper bearing-plate, and at its lower end the lower bearing-plate, said upper bearing-plate having depending sides embracing the spacer and provided with guide-flanges, and 95 said lower bearing-plate being provided with guide-plates overhanging the guide-flanges on the depending sides of the upper bearing-plate, substantially as specified.

8. In a roller side bearing, the combination 100 with an upper bearing-plate, of a lower bearing-plate provided with reversely-inclined roller-tracks, a pair of rollers interposed between said upper and lower bearing-plates, spacer-plates connecting said rollers, and a 105 roller-positioning device pivotally connected to said spacer-plates, and engaging at its upper end the upper bearing-plate and at its lower end the lower bearing-plate, substantially as specified.

9. In a roller side bearing, the combination 110 with an upper bearing-plate, of a lower bearing-plate provided with reversely-inclined roller-tracks, a pair of rollers interposed between said upper and lower bearing-plates, 115 spacer-plates connecting said rollers, and a roller-positioning device pivotally connected to said spacer-plates, and engaging at its upper end the upper bearing-plate and at its lower end the lower bearing-plate, said upper 120 bearing-plate having depending sides furnished with guide-flanges and said lower bearing-plate having guide-plates overhang-said guide-flanges, substantially as specified.

JOHN F. O'CONNOR.
